UNITED STATES PATENT OFFICE

WILLIAM H. GILLIS, OF HUMBLE, TEXAS, ASSIGNOR OF ONE-FOURTH TO D. H. GUNN
AND ONE-FOURTH TO H. B. GUNN, BOTH OF HARRIS COUNTY, TEXAS

BURNER

Application filed December 3, 1931. Serial No. 578,723.

This invention relates to a burner.

An object of the invention is to provide a burner of the character described particularly designed for the purpose of utilizing crude petroleum, and similar products, for fuel.

Another object is to provide a burner so constructed that the fuel may be heated and wholly or partly vaporized before it is discharged into the combustion chamber and ignited.

Another object is to provide a burner which is of very simple construction, may be cheaply produced, which will not be liable to get out of order and which is very efficient for the purposes intended.

With the above and other objects in view this invention has particular relation to certain novel features of construction, operation and arrangement of parts an example of which is given in this specification and illustrated in the accompanying drawing, wherein:—

Figure 1 shows a longitudinal sectional view of the burner, and

Figure 2 shows a cross sectional view taken on the line 2—2 of Figure 1.

Referring now more particularly to the drawing, wherein like numerals of reference designate similar parts in each of the figures the numerals 1 and 2 designate outer and inner tubular jackets concentrically arranged and spaced apart. The chamber 3 between these jackets is closed by the annular end plates 4, 5 which are welded, or otherwise secured to the ends of these jackets.

Spanning said chamber are the lengthwise partitions 6, 7, which extend inwardly from the end plate 4 and which fit closely against said jackets and said end plate and whose inner ends are spaced from the end plate 5.

A fuel supply line 8 enters the outer end 45 of the chamber 3 on one side of the partition 7 and a fuel feed pipe 9 leads out from the outer end of said chamber from the opposite side of the partition 6.

There is an elongated steam nozzle pipe 50 10 arranged axially within and spaced from

the inner jacket 2 and this steam nozzle pipe terminates in a nozzle 11. The outer end of the steam nozzle pipe has a stuffing box 12 through which the fuel feed pipe 9 is fitted and this pipe 9 terminates in a fuel nozzle 13 within the nozzle 11.

Entering the outer end of the steam nozzle pipe there is a steam line 14 through which steam, or air, under pressure, may be supplied to the pipe 10.

The burner may be mounted in the front wall 15 of the combustion chamber with its inner end projected well into said chamber.

The fuel, preferably crude petroleum, will be supplied into the chamber 3, through the line 8 and will travel along on one side of the partitions 6, 7 toward the outer end of said chamber and will be heated and wholly or partly vaporized therein and will pass around the inner ends of said partitions and back toward the outer end of the chamber 3 and will pass thence through the nozzle pipe 9. Steam, or air, under pressure will be forced through the line 14 and nozzle pipe 10 out past the nozzle 13 and through the nozzle 11 and will further vaporize the fuel issuing out through the nozzle 13. Air will flow inwardly through the inner jacket and the vaporized fuel will be mingled therewith and the mixture will be forced, in combustible, vaporous form into the combustion chamber where it is ignited and consumed.

The chamber 3 is provided with a drain cock 14 through which water that may condense therein may be drained therefrom.

The drawing and description disclose what is now considered to be a preferred form of the invention by way of illustration only while the broad principle of the invention will be defined by the appended claims.

What I claim is:—

1. A burner comprising a tubular body composed of an outer and an inner jacket defining a chamber between them, a nozzle pipe extending axially through the inner jacket and terminating in a nozzle, a fuel supply pipe entering the outer end of the chamber, a feed pipe leading out from the 100

outer end of the chamber and extending co-axially through the nozzle pipe and terminating in a fuel nozzle, and means for confining the fuel in the chamber to movement in a longitudinal course therealong.

2. A burner comprising a tubular burner body composed of an outer jacket and an inner jacket spaced from the outer jacket, said jackets defining a closed chamber said inner jacket defining an air passageway, a nozzle pipe extending axially into, and terminating in, said passageway, lengthwise partitions spanning the chamber and extending lengthwise from the outer end thereof and being spaced from the inner end thereof, a fuel supply pipe entering the outer end of the chamber on one side of said partitions, a fuel feed pipe leading from the outer end of said chamber on the other side of said partitions and extending axially through and terminating in said nozzle pipe adjacent the inner end thereof.

3. A burner comprising a tubular burner body composed of an outer jacket and an inner jacket spaced from the outer jacket, said jackets defining a closed chamber said inner jacket defining an air passageway, a nozzle pipe extending into said passageway

and terminating in a nozzle therein, lengthwise partitions spanning the chamber and extending from the outer end thereof and being spaced from the inner end thereof, a fuel supply pipe entering the outer end of the chamber on one side of said partitions, a fuel feed pipe leading from the outer end of said chamber on the other side of said partitions and extending axially through, and terminating in, said nozzle pipe and nozzles on said terminating ends of said nozzle pipe and feed pipe.

4. A burner comprising a tubular body having an axial air passageway therethrough and having a closed chamber around said passageway, a fuel supply line entering the outer end of the chamber, a fuel feed line leading out from said outer end of the chamber, partitions spanning said chamber between, and on opposite sides of, said lines and leading from the outer end of the chamber and spaced from the inner end thereof, a nozzle pipe projecting into said passageway, said feed line extending into said nozzle pipe and nozzles on the inner ends of said nozzle pipe and feed line respectively.
